(Model.)

D. H. METCALF,

Window and Door Screen.

No. 241,688.

Patented May 17, 1881.

N. PETERS, Photo-Lithographer, Washington, D. C.

UNITED STATES PATENT OFFICE.

DAVID H. METCALF, OF BATTLE CREEK, MICHIGAN.

WINDOW AND DOOR SCREEN.

SPECIFICATION forming part of Letters Patent No. 241,688, dated May 17, 1881.

Application filed January 2, 1880.

To all whom it may concern:

Be it known that I, DAVID H. METCALF, of Battle Creek, in the county of Calhoun and State of Michigan, have invented certain new and useful Improvements in Window and Door Screens; and I do hereby declare that the following is a full, clear, and exact description of the same, reference being had to the accompanying drawings, in which—

Figure 1 is an outside elevation of a window-screen embodying my improvements. Fig. 2 is a vertical sectional view of the same; and Fig. 3 is a horizontal sectional view through one of the side bars, showing the manner of connecting the wire-cloth thereto. Fig. 4 is a horizontal sectional view on line $\alpha\alpha$ in Fig. 1, and Fig. 5 is an end view of the corner.

This invention has relation to window and door screens; and it consists of the improved features of construction and combination hereinafter fully described, and particularly pointed out in the claims.

Referring by letter to the accompanying drawings, A designates the wire-cloth with which the screen-frame is covered.

B designates the top bar, and B' the bottom bar or rail, of the screen-frame proper; and ff, the vertical side bars of the same.

C C designate vertical auxiliary or extension side bars, secured to pins d d working in recesses d' in the ends of the top and bottom bars, B B'. The bars C C are secured to the faces of the pins d, and come about flush with the outside of the frame proper.

In constructing the side bars, ff, their lower ends are kerfed about midway longitudinally and from edge to edge, as at g', Figs. 4 and 5, first rabbeted at their ends to receive the tenons on the top and bottom bars, B B', and then a block, g, cut off, the cross-cut being made at the upper termination of the kerf, as at g², Fig. 1, and the block secured in the space it formerly occupied by a nail until the frame is put together, when the nail will be unnecessary, although it may remain. The purpose of the blocks g will be hereinafter explained.

A top rail, h, is pivoted at its center to the upper bar, B, by a pivot or screw, i, and is provided on one edge with a flexible cushion, b', of rubber or the like.

The pins d are provided with suitable stops,

which prevent them from being forced entirely out of their recesses d', and they are operated by springs d², which keep the bars C C normally extended.

The rear faces of the bars B B' are grooved at c, and tongues c' are employed to fasten the wire-cloth A to them and bring it flush with the outside of the frame. The rear faces of the bars ff are rabbeted, as seen in Fig. 3, and an L-shaped molding, e, is employed to bind the edges of the cloth A to the side bars, ff.

Near the upper edge of the wire-cloth A are perforations a a, made either by being woven in the fabric or by being punched with any suitable instrument.

On the inside of the frame, and pivoted to the side bars, ff, directly beneath the top bar, B, is a damper, b, for opening and closing the apertures a a.

The extension bars C C are not new in this connection, but are employed to cause the screen-frame to fit snugly. The top rail, h, should be made as long as the frame with the extensions expanded, and may be cut off when the frame is adjusted to the window, if necessary. The cushion b fits snugly against the sash, or the glass and sash where the window is only partially raised. The top rail may be turned on its pivot to bring the cushion either on the inside or the outside of the screen-frame, so that the screen may be used equally as well on the outside as on the inside, where necessary or desirable.

In day-time the damper is left open, and the insects in the room will naturally seek the light, and will find the outlets a a and escape. At night the damper is closed to prevent the entrance of insects. The cloth is made flush with the outside of the frame, in order that there may be no shadow thrown from the outside over the outlets a, which would darken them and lessen their usefulness.

The blocks g are intended to be used only when it is necessary to shorten the screen-frame, and as this cannot always be readily done with the appliances at command they are of some importance. The lower bar, B', should be loosened from its connections and the blocks g entirely removed, if necessary, or cut off a proper distance and the remaining portion replaced. The wire-cloth is also cut off and a new tenon formed, the other parts be-

ing reduced accordingly. Thereby the cost of a new screen is saved.

Having thus fully described my invention, what I claim as new, and desire to secure by 5 Letters Patent of the United States, is—

1. In a window-screen, the pivoted reversible top rail, *h*, provided with the flexible cushion *b'*, in combination with the top bar, *B*, of the screen-frame, substantially as and for the 10 purposes set forth.
2. In a window-screen, the side bars, *ff*,

provided with the removable blocks *g*, substantially as and for the purposes set forth.

3. In a window-screen, the wire-cloth *A*, provided near its upper edge with the series of 15 outlets *a*, in combination with the damper *b*, substantially as and for the purposes set forth.

DAVID H. METCALF. [L. S.]
